UNITED STATES PATENT OFFICE.

HARRY HARDWICK, OF PHILADELPHIA, PENNSYLVANIA, ASSIGNOR TO IVINS, DIETZ & METZGER COMPANY, OF PHILADELPHIA, PENNSYLVANIA, A CORPORATION OF PENNSYLVANIA.

STRETCHING DEVICE FOR CARPETS AND RUGS.

No. 873,743.

Specification of Letters Patent.

Patented Dec. 17, 1907.

Application filed October 24, 1906. Serial No. 340,325.

To all whom it may concern:

Be it known that I, HARRY HARDWICK, a citizen of the United States, residing in Philadelphia, Pennsylvania, have invented certain 5 Improvements in Stretching Devices for Carpets and Rugs, of which the following is a specification.

The object of my invention is to provide simple and efficient means for stretching carpets or rugs and retaining them in a stretched 10 condition while they are drying, and while, in the case of pieced rugs, the seams between the sections are being flattened by ironing the same.

15 In the accompanying drawing:—Figure 1 is a view of a stretching frame and its appurtenances made in accordance with my invention; Fig. 2 is a perspective view, on an enlarged scale, of one of the retaining 20 clamps used in connection with the stretching frame; Fig. 3 is an enlarged transverse section on the line *a—a*; Fig. 1; Fig. 4 is an enlarged transverse section on the line *b—b*, Fig. 1, and Fig. 5 is an enlarged transverse 25 section on the line *c—c*, Fig. 1.

In the manufacture of rugs it is the customary practice to stretch the same, and to wet or dampen them and permit them to dry while retained in the stretched condition, and it has been the purpose of my invention to provide more effective devices than those now employed for effecting such stretching of the rug and its subsequent retention in a stretched condition.

35 In the drawing, 1 represents a rectangular frame, which is usually composed of wood and is provided with a central filling piece or body 2 in order to provide proper support for all portions of the rug which is being 40 stretched, and thereby permit the ready flattening of the seams 3, whereby, in the case of a pieced rug, the sections of the rug are secured together, such flattening being effected by means of a pressing iron moved 45 back and forth along the seam.

Along one side of the frame is a row of outwardly inclined pins 4 and along one end of the frame is a row of similar pins 5, while along the opposite side of the frame is a row 50 of straight pins 6, and at the opposite end of the frame is a row of straight pins 7, the pins 4 and 5 being inclined, in order to better resist the strain exerted upon them by the rug during the stretching operation.

The clamping devices are located at the 55 corners of the rug and along the sides and ends of the same, their disposition along the sides of the rug being such as not to interfere with the action of the pressing iron upon the seams 3. Each clamp consists of a pair of 60 parallel bars 9 and 10, connected at the ends by transverse handles 11, preferably raised above the level of the bars whereby the clamp can be conveniently manipulated. The bar 9 of the clamp has at each end a long 65 depending pin 12, and between these end pins a series of shorter depending pins 13, and the bar 10 has a centrally disposed long depending pin 14. When, therefore, the clamp-frame is pressed down upon the back 70 of the rug, the pins 12 and 14 pass through the rug and engage with the frame 1 so as to firmly retain the clamp in position and prevent any twisting or distortion of the same, while the shorter pins 13 only penetrate the 75 material of the rug and thus aid in the retention of the rug in the stretched condition without engagement with the frame 1, proper engagement of each clamp with the frame 1 being thereby effected with the minimum 80 amount of mutilation of the latter. The location of the handles 11 between the two sets of pins of each clamp provides for the application of the maximum amount of force to the pins and insures the proper penetration 85 of the frame 14 thereby.

The use of the clamping frames provides for the engagement of the rug with a number of pins at one time, and consequently facilitates the securing of the rug to the frame as 90 compared with the application of the rug to a single pin at a time, and the disposition of the pins on the clamp in two planes insures the more secure confinement of the clamp to the stretching frame than would be possible 95 if a single row of pins only was used.

In applying the rug to the frame, one of the side portions of the rug is stretched longitudinally and secured in position by application to the inclined pins 4 and by the 100 clamps, and at the same time or subsequently one of the end portions of the rug is stretched transversely and secured by application to the inclined pins 5 and by the clamps, the opposite side and end of the rug being then 105 stretched and secured in position by application to the pins 6 and 7, respectively and by the clamps, the use of the straight pins 7,

preventing any slackening of the rug after it has been applied thereto.

By the use of the clamps in combination with the fixed pins, said clamps are relieved 5 of a great portion of the strain which would tend to dislodge them, while on the other hand the clamps effectually prevent the release of the rug from the control of the fixed pins.

10 I claim:—

1. The combination of a rug stretching frame having permanent pins, with removable clamps provided with pins for engaging the rug and frame independently of the fixed 15 pins of the latter.

2. The combination of a rug stretching frame, with a clamp disconnected from said frame and having pins for passing through a rug stretched on the face of the frame, said 20 pins engaging the frame after passing through the rug.

3. A rug holding clamp for stretching frames having long pins for passing through the rug and engaging the frame, and short 25 pins for engaging the rug only.

4. A rug holding clamp for stretching frames having pins at opposite ends, and a

centrally disposed pin laterally separated from the end pins.

5. A rug holding clamp for stretching 30 frames having long pins at opposite ends, intermediate shorter pins, and a centrally disposed long pin laterally separated from the end pins.

6. A rug holding clamp for stretching 35 frames having pins in different planes and handles disposed between said pins.

7. A rug holding clamp for stretching frames composed of two bars, and handles connecting said bars at the ends of the clamp, 40 the bars of the clamp being provided with depending pins.

8. A rug holding clamp for stretching frames composed of opposite bars with depending pins, and raised handles connecting 45 the bars at the opposite ends of the same.

In testimony whereof, I have signed my name to this specification, in the presence of two subscribing witnesses.

HARRY HARDWICK.
